CORONA FREE MULTIPLIER

Bernard W. Smith, Winston-Salem, N. C., assignor to Western Electric Company, Incorporated, New York, N. Y., a corporation of New York

Application June 14, 1951, Serial No. 231,541

9 Claims. (Cl. 201—63)

1

This invention relates to electrical instrument multipliers and more particularly to a multiplier having corona free construction.

In making voltage measurements, a current-sensitive meter is placed in series with a multiplier to produce a voltage indicator which will include a desired range of voltages. At high voltages, the customary meter and multiplier combination is unsatisfactory since corona, resulting from the high potential gradient, introduces a shunt path to by-pass the indicating meter. Efforts to eliminate the losses due to corona discharge have been unsuccessful or, at best, have produced bulky and unwieldy devices.

An object of the present invention is to provide an instrument multiplier that can be utilized in high voltage circuits without incurring any losses because of corona and which can be used for accurate voltage determinations in a high voltage range.

In accordance with one embodiment of the invention, there is provided a multiplier having a plurality of carbon resistors which are interconnected by smooth rounded supporting members and are suspended from these supporting members within a group of insulating tubes. The insulating tubes are positioned within a cylinder made of an insulating material and are held in spaced relation by fiber discs fitted within the cylinder for that purpose. The cylinder is closed at both ends by rounded metallic end members which also serve as electrical terminals for the assembly. The unit is then impregnated with an oil which has a high dielectric strength and the assembly is mounted vertically on a base of insulating material. All of the parts are machined to have round edges and polished to remove machine marks so as to reduce the tendency toward atmospheric discharge at high voltages.

A complete understanding of the invention may be obtained from the following detailed description taken in conjunction with the accompanying drawing, in which:

Fig. 1 is a longitudinal section illustrating one embodiment of the invention.

Fig. 2 is a cross-sectional view taken along line 2—2 of Fig. 1 showing the electrical interconnection of the tubes of resistors;

Fig. 3 is an enlarged detailed view of a supporting connector illustrating the suspension of resistance elements within one of the tubes;

Fig. 4 is a fragmentary perspective of an end of one of the tubes and showing a slot for retaining a supporting connector;

2

Fig. 5 is a fragmentary view taken along line 5—5 of Fig. 2 illustrating the supporting means for the tube positioning discs; and

Fig. 6 is a partial sectional view taken along line 6—6 of Fig. 1 showing means for establishing an electrical connection in the base.

Referring now to the drawing wherein like reference numerals designate the same parts throughout the several views, and more particularly to Fig. 1 wherein an insulating cylinder 21 of a ceramic material is closed at both ends by rounded metallic end closures 22 and 23 threaded thereon, terminals 24 and 25 are fitted into apertures in the end closures 22 and 23, respectively, and are secured in place by solder fillets. The upper end of terminal 24 is threaded into a metal cap member 26 which is adapted to be connected to a plug 19 from an electrical apparatus being tested.

20 End closure 23 rests upon an insulating base 27 which has a metallic insert 28 which serves as an electrical conductor (Fig. 6) and has a kilovolt meter 29 connected thereto.

The cylinder 21 has mounted within it a resistor assembly including insulating discs 20 which are notched to engage vertical supporting members 11 correspondingly notched as shown in Fig. 5. Insulating tubes 12 are tightly fitted into spaced apertures in the discs 20 and thus are held in predetermined spaced relation within cylinder 21.

35 A plurality of electrical resistors 13 are suspended within each tube 12 and are connected in series by small rounded metallic connectors 14 which have a central bore into which the terminal wires of two resistors are inserted from opposite ends. Solder is then applied to the connector 14 and it is burnished to remove all sharp corners and rough edges.

40 The series chains of resistors 13 in the various tubes 12 are interconnected in series by smooth rounded supporting connectors 15 which rest in notches on the insulating tubes 12 (Figs. 3 and 4). Terminal leads 16 at the ends of the entire series chain of resistors 13 are connected to the terminals 24 and 25 by insertion in a central bore thereof and secured therein with a solder seal. Attached to each terminal lead 16 is a metallic disc 17 which maintains the resistors centrally oriented within the tubes 12.

55 The cylinder 21 is evacuated and vacuum impregnated through apertures 18 in the end closure 22 with a fluid of high dielectric properties, such as transil oil, after which said apertures are sealed with solder.

This meter multiplier may be permanently secured at a test station or used as a portable unit and may be used to measure voltages up to 40 kilovolts without corona breakdown occurring.

Although the invention has been described with reference to one particular embodiment, it is to be understood that various modifications may be made without departing from the spirit and scope of the invention.

What is claimed is:

1. In an electrical instrument multiplier, a receptacle of insulating material, rounded end members for sealing said receptacle, a plurality of hollow insulators retained in spaced relation within said receptacle, a plurality of resistors 15 within said hollow insulators and electrically interconnected, and a terminal retained in each member connected to the resistors and adapted for connection to the electrical instrument.

2. In an electrical instrument multiplier, a receptacle of insulating material, rounded metallic end members for sealing said receptacle, a plurality of hollow insulators retained in spaced relation within said receptacle, a plurality of series connected resistors retained within said hollow 25 insulators and connected to said end members, and a dielectric fluid substantially filling said receptacle to prevent corona discharge at high voltages.

3. In an electrical meter multiplier, a cylinder 30 of insulating material, metallic members for closing the ends of said cylinder, a plurality of hollow insulators, means for retaining said hollow insulators in a predetermined spaced relationship within the cylinder, a plurality of series connected resistors within said hollow insulators and connected to said end closing members, and a dielectric fluid substantially filling said cylinder.

4. A corona free multiplier comprising a cylinder of insulating material, members of conducting material for closing the ends of said cylinder, a plurality of spaced insulating tubes positioned within said cylinder, a plurality of resistance elements connected in series and positioned within said tubes and connected to said 45 end members, and a dielectric fluid substantially filling the said cylinder.

5. In an electrical instrument multiplier, an insulating cylinder, a plurality of hollow insulators, means for retaining the hollow insulators in a predetermined spaced relationship within the cylinder, a plurality of resistors, connectors having smooth rounded surfaces for interconnecting the resistors in series within the hollow insulators, metallic members connected to the resistors and having smooth and curved surfaces for closing the ends of said cylinder and to prevent corona, and a dielectric fluid substantially filling the closed cylinder.

6. A corona free multiplier comprising a cylinder of insulating material, closure members of conducting material for sealing the ends of said cylinder, a plurality of spaced insulating tubes positioned within said cylinder, a plurality of resistance elements connected in series and positioned within said tubes and connected to said end closure members, an insulating base, and a conductor secured in said base and connected to one of said end closing members for connection with an electrical instrument to determine the 60 voltage range thereof.

7. In a corona free electrical instrument multi-

plier, a cylinder of insulating material, a plurality of insulating tubes, means for retaining the insulating tubes in a predetermined spaced relationship within said cylinder, resistors of predetermined value, metallic connectors having smooth rounded surfaces for connecting said resistors in series within the insulating tubes, smooth rounded metallic connectors supported by the tubes for retaining the series of interconnected resistors therein and interconnecting them from tube to tube, and metallic end members connected to the resistors and having smooth rounded surfaces for closing the ends of said cylinder.

8. In an electrical instrument multiplier, a smooth ceramic cylinder threaded at each end, notched supports positioned against the internal wall of said cylinder, insulating discs having notched portions for engagement with the notched supports and having spaced apertures, insulating tubes positioned within the spaced apertures of the discs, resistors of predetermined value connected in series within each tube, smooth rounded connectors for supporting the series of interconnected resistors in the tubes and for interconnecting them from tube to tube, means for supporting the connectors at predetermined ends of said tubes, smooth rounded metallic end closures threaded onto the ends of the cylinder, a terminal secured in each of said end closures, means for connecting one of the two ends of the interconnected resistors to one of the terminals and the other end thereof to the other terminal, and a dielectric substantially filling the ceramic cylinder.

9. In an electrical instrument multiplier, a smooth ceramic cylinder threaded at each end, notched supports positioned against the internal wall of said cylinder, insulating discs having spaced apertures, insulating tubes positioned within the spaced apertures of the discs, resistors of predetermined value connected in series within each tube, smooth rounded connectors for supporting the series of interconnected resistors in the tubes and for interconnecting them from tube to tube, means for supporting the connectors at predetermined ends of said tubes, smooth rounded metallic end closures threaded onto the ends of the cylinder, metallic terminals connected to the ends of the series of resistors and secured in said end closures, a base, a conductor secured in said base and connected to the terminal in one of said end closures and connected to the electrical instrument to determine the voltage range thereof, and a dielectric fluid substantially filling said cylinder.
